UNITED STATES PATENT OFFICE.

CLYDE L. WELSH, OF PITTSBURGH, PENNSYLVANIA.

FEED GUIDE FOR PRINTING PRESSES.

1,403,662.

Specification of Letters Patent. Patented Jan. 17, 1922.

Application filed June 15, 1921. Serial No. 477,659.

To all whom it may concern:

Be it known that I, CLYDE L. WELSH, a citizen of the United States, residing at Pittsburgh, in the county of Allegheny and

5 State of Pennsylvania, have invented certain new and useful Improvements in Feed Guides for Printing Presses, of which the following is a specification.

This invention relates to feed guides for 10 printing presses to facilitate the positioning of the paper upon the platen prior to the printing operation.

Objects of the invention are to provide a device of the character described, in a manner as hereinafter set forth, which is simple 15 in its construction and arrangement, strong, durable and efficient in its use, readily positioned, which permits of printing closely thereto, and which is comparatively inexpensive 20 to manufacture.

To the accomplishment of these and such other objects as may hereinafter appear, the invention consists of the novel construction, combination and arrangement of parts herein 25 specifically described, and illustrated in the accompanying drawing wherein is shown an embodiment of the invention, but it is to be understood that changes, variations and modifications may be resorted to which 30 come within the scope of the claims hereunto appended.

In the drawing forming a portion of this specification and wherein like numerals of reference designate corresponding parts 35 throughout the several views:

Figure 1 is a top plan view of a plurality of feed guides attached to a draw sheet.

Figures 2 and 3 are enlarged top and bottom plan views, respectively, of the guides, 40 in accordance with this invention.

Figure 4 is a sectional view on line IV—IV. Figure 2.

Figure 5 is a rear elevation of the device.

Figures 6 and 7 are enlarged detail perspective views of the wedge member and the gauge member, respectively.

Figure 8 is a top view of the tongue member.

Referring in detail to the drawing 1 de- 50 notes the body portion preferably constructed from sheet metal and rectangular in contour. The bottom portion 2 thereof is formed to provide a pair of forwardly projecting pointed prongs 3. The ends of the 55 body portion 1 are open, and the top of each

of the side members 4 of the body portion is provided with a longitudinally extending flange 5 having enlarged rear and forward ends 6.

A gauge member 7, provided with an 60 angularly disposed depending head 8, is pivotally connected in the rear lower end of the body portion 1 by means of the shaft 9, which passes through the apertures 10 in the side members 4 and through the apertured ears 11 of the gauge member 7. The head 8 is formed integral with the forward end of the gauge member 7 and has its lower edge provided with notches 12, which latter are adapted to overlap the points of the 70 prongs 3. The rear end of the gauge member 7 has an upwardly disposed arm 13 formed integrally therewith.

Slidably mounted in the body portion 1, on top of the gauge member 7, is a wedge 75 member 15 provided, at each side thereof, with a forwardly tapering side member 16. The rear end of the wedge member 15 is formed with a vertically extending portion 17 having a rearwardly disposed lug 18 80 punched therefrom.

The gauge member 7 and the head 8 thereof, at the point of juncture, are formed with a slot 19 for the insertion of a resilient tongue member 20, adapted to extend through 85 85 and project from the body portion 1, beneath the gauge member 7.

In practice the operation of the feed guides is as follows: By sliding the wedge member 15 rearwardly the lug 18 thereof 90 will strike the arm 13 of the gauge member 7, thereby lifting the head 8 clear of the prongs 3. The device is attached to the draw sheet positioned on the platen of the printing press, by inserting the prongs 3 95 into and beneath the draw sheet and then sliding the wedge member 15 forwardly thereby forcing the head 8 upon the prongs 3 beneath the draw sheet. The action of the notches 12 upon the prongs 3 will serve to 100 augment the gripping action therebetween. The flanges 5 of the body portion 1 engage the wedge member 15, when the latter is slid in the forward direction to secure the device upon the draw sheet. The vertical 105 portion 17, of the wedge member 15, extending above the body portion 1, facilitates the manipulation of the wedge member 15. The enlarged rear and forward ends 6, of the flanges 5, retains the wedge member 15 in 110

the assembled position, as the vertical portion 17 thereof is of greater width than the space between either of the ends 6.

The device may be used either with or without the tongue member 20. It is employed to facilitate the positioning of the sheet to be printed upon the draw sheet, but would not be used when printing closely to the guide. The tongue 20, being resilient, may be frictionally drawn and held in the body portion 1 in any position desired.

What I claim is:

1. A feed guide for the purpose comprising a body portion provided with prongs, a gauge member pivotally connected in the said body portion, and a wedge member slidably mounted in the body portion for forcing said gauge member against the said prongs.
2. A feed guide for the purpose set forth comprising a body portion provided with a pair of forwardly disposed prongs, a gauge member pivotally connected in the said body portion and including a depending head, and a wedge member slidably mounted in the

body portion for locking said head against said prongs.

3. A feed guide for the purpose set forth comprising a body portion provided with a pair of prongs, a gauge member pivotally connected in said body portion and including a depending head, said head formed with a pair of notches adapted to overlap said prongs, and a wedge member slidably mounted in the body portion for holding said gauge member on said prongs.

4. A feed guide for the purpose set forth comprising a body portion provided with a pair of prongs, a gauge member pivotally connected in said body portion and including a depending head engaging said prongs, a wedge member slidably mounted on said gauge member in said body portion, and associated means carried by the wedge member and the gauge member for releasing said head from said prongs by the sliding movement of the wedge member.

In testimony whereof I affix my signature.

CLYDE L. WELSH.
